5 Sheets-Sheet 3

<img alt="A detailed technical drawing of a mechanical device, labeled Fig. 3. The drawing shows a complex assembly of gears, levers, and springs. Key components include a flywheel at the top (labeled 73), a central gear assembly (labeled G), and various numbered parts (e.g., 1, 5, 10, 12, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, 100, 101, 102, 103, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, SHOE-HEEL-CONCAVING MACHINE

Peter J. Muschong, Peter Parr, and Joseph W. Oberbeck, St. Louis, Mo., assignors to United Wood Heel Company, St. Louis, Mo., a corporation of Delaware

Application March 21, 1932, Serial No. 600,198

35 Claims. (Cl. 12—46)

This invention relates generally to shoe-heel manufacture and has more particular reference to a machine for concaving heels for shoes and the like.

5 Heretofore, so far as we are aware, the concaves or so-called cups of heels for shoes and the like have been finished by means of a side-mill or cutter against or to which the heel or work is manually fed by manipulating the heel in inverted position on and over the cutter with an irregular movement suitable for grooving and forming the heel cup or concave in the (inverted) heel-body.

It has also heretofore been the practice to employ for such heel concaving purposes, so far as we are also aware, so-called side-mills or cutters whose cutting edges work toward the edge of the concave with a frequently resulting defective product by reason of chipping or slivering of the concave-rim.

20 In commercial practice, moreover, it has been found that the operator, no matter how skillful he may be, is, of course, unable to approach uniformity in the performance of the heel-grooving operation; hence it may often occur that the rejects in this class of work will be as much as thirty percentum (30%) of the operator's output. Again, and of more serious consequence, inevitably the necessarily close proximity of the operator's hand to the cutter results in hand-maiming accidents, so that few operators in the trade are free from maimed or injured fingers and hands.

Our invention has hence for its prime object the provision of a heel-concaving machine for automatically feeding a heel to and from a heel concaving or cup-grooving cutter for both improving the rate and quality of production of concaved-heels and for substantially eliminating the dangers of the heel concaving operation as heretofore practiced.

40 Our invention has for another object the provision of a heel-concaving machine embodying a cutter of the vertical or end-mill type having its cutting edge working from the rim of the concave towards the center thereof for substantially avoiding slivering and chipping of the heel-rim during the production of concaved-heels.

And with the above and other objects in view, our invention resides in the novel features of form, construction, arrangement, and combination of parts hereinafter described and pointed out in the claims.

In the accompanying drawings (5 sheets).—

Figure 1 is a front elevational view, partly broken away and in section, of a shoe-heel-concav-55 ing machine embodying our invention, taken ap-

proximately along the line 1—1, Figure 3, the machine being shown in position for advancing or feeding a heel to the cutter;

Figure 2 is a side elevational view of the machine, the lower portion of the frame being broken away;

Figure 3 is a top plan partly sectional view of the machine, taken approximately along the line 3—3, Figure 2;

Figure 4 is an enlarged fragmental top plan 10 view of the indexing mechanism of the machine shown as at the end of its indexing movement, the normal position thereof being indicated by dot-dash lines;

Figure 5 is a fragmental vertical longitudinal 15 sectional view of the machine, taken approximately along the line 5—5, Figure 3, the extreme rear and lower portions of the machine being broken away;

Figure 6 is a fragmental vertical transverse 20 sectional view of the machine, showing the heel-concaving cutter in operation for forming a heel-concave, the heel-holding chuck and parts co-operating therewith being sectionally shown and other parts omitted;

Figure 7 is a top plan view, partly broken away and in section, of the carriage of the machine, the work-table being omitted, and the carriage shown in rearwardly shifted heel-feeding position;

Figure 8 is a fragmental vertical sectional view 25 through the toggle mechanism of one of the heel-chucks of the machine, taken approximately along the line 8—8, Figure 3; and

Figure 9 is a diagrammatic view illustrating 30 the path of the cutter with respect to the heel for grooving the concave therein.

Referring now more in detail and by reference characters to the drawings, which illustrate a preferred embodiment of our invention, the machine includes a horizontal bed-plate A supported, as from a floor or other suitable foundation, by means of a frame preferably comprising suitable corner posts or standards 1, the bed-plate A supporting, in turn, by means of suitably provided 40 corner-pedestals, a plurality of, in the present instance four, transversely spaced and longitudinally aligned vertical pins 2 each at its upper end terminating in a preferably hardened and rounded nose or point-bearing, as best seen in 45 Figures 1 and 2.

Supported for universal horizontal movement slidably on the point-bearings 2, is a reciprocable carriage B comprising a relatively flat horizontal plate or body-member provided near its front 50

margin with a pair of concentric inner and outer circular heel-supports in the form of annular raised-ribs 3, 4, respectively, the centers of the ribs 3, 4, coinciding with the axis of a fixed stud 5 or pintle 5 suitably threaded into, and upstanding from, the approximate forward central portion of the carriage B, as best seen in Figure 7.

Axially journaled on a collar 6 of the pintle 5, is an approximately circular indexing-table or work-support C supported by, and for rotatory or circular sliding movement on, the raised annular ribs 3, 4, of the carriage B, as best seen in Figure 5.

Mounted on the table C, is an indexing-mechanism D, which includes an annular series of pillars or posts 7 upstanding from the table C for suitably supporting a horizontal ratchet hub-plate 8 carrying a vertical stud 9 disposed in the axis of, and for rotation with, the table C. Spaced from, and likewise adapted for rotation with, the plate 8, is a ratchet-wheel 10 preferably, for structural reasons, seated on a collar 11 of the stud 9, a suitable cap 12 being threaded on the stud 9 for retaining the ratchet 10 thereon. The ratchet 10 is provided with a series of, preferably four, circumferentially spaced ratchet-teeth 13 engageable successively by and with a pawl 14 pivotally, as at 15, mounted on a pawl-plate 16 journaled or bushed on the stud-collar 11 for oscillatory movement between the hub-plate 8 and the ratchet 10. The pawl 14 includes an arm engaged by a spring 17 supported from the plate 16 for normally biasing the pawl 14 against the toothed periphery of the ratchet 10, as best seen in Figures 4 and 5, whereby, as will be understood, oscillation of the pawl-plate 16 results in engagement of the pawl 14 successively with the respective teeth 13.

To the free or outer end of the pawl-plate 16, is pivoted one end of a link 18 having in its other end a so-called lost-motion slot 19, in which works a block or slide 20 carried on a crank-pin 21 of a crank 22 mounted on the upper end of a vertical shaft 23 journaled in respective upper and lower bearings 24 mounted, in turn, on a vertical member 25 projecting from the frame of the machine, all as best seen in Figure 4. The shaft 23, at its lower end, carries a gear 26 meshing with a pinion 27 mounted on the vertical shaft 50 of a speed-reducer 28 driven by a motor 29, all said parts being supported in any suitable manner by and on the frame of the machine, as will be understood, whereby each revolution of the shaft 23 serves for intermittent step by step partial rotatory movement or, in the present instance, one-quarter revolution, of the indexing-table C for a purpose presently appearing.

Mounted on the under face of the indexing-table C, is a plurality of heel-gripping chucks E. In the present instance, four of the chucks E are arranged on, and adjacent the periphery of, the table C in quadrature or 90 degrees circumferentially apart, as best seen in Figure 3, each chuck E including a pair of spaced levers 30 pivoted for swingable movement on respective upstanding studs or pintles 31.

Supported rockably, as at 32, from the respective outer ends of the levers 30, is a pair of opposed jaws 33 each having an arcuate face provided adjacent its lower margin with a longitudinal notch or channel 34 for gripping engagement with the marginal lateral portion or rim 35 of a heel G, as will presently more fully appear, the jaws 33 depending from the levers 30 for heel-gripping movement in suitably shaped apertures

or pockets 36 provided in the periphery of the table C, as best seen in Figures 3 and 6.

The heel G, for chuck-gripping purposes, is initially in inverted position disposed upon the portions of the tracks 3, 4, exposed through the apertures 36 for alignment of the heel-rim 35 with the jaw-notches 34 and with the breast of the heel facing front-wise for positioning the "toe" or shank lip of the heel G radially-outwardly with respect to the axis of the table C, the heel being brought outwardly for engagement of its breast with the rear or inner face of a plate 37 having depending lateral guide-flanges 38 slidably engaging corresponding ways 39 in a bracket 40 projecting radially from the periphery of the table C. The plate 37 is provided with a longitudinal slot 41 working over the shank of a suitable fastening element or thumb-screw 42 threaded into the bracket 40, whereby the inner face of the plate 37 may be gauged or adjusted to the desired radial distance from the table-center suitable for the proper operation of the machine upon different sizes and shapes of heels, as presently appearing.

At their respective inner ends, the levers 30 of each chuck E are suitably bifurcated for respective pivoted connection, as by a stud 43, with a pair of toggle-links 44 having knuckled pivoted connection, as at 45, in the bifurcated end of, and with, a block 46 slidably mounted for radial reciprocation in opposed parallel ways 47 mounted suitably for such purpose upon the upper side of the table C, as best seen in Figures 3 and 8, whereby, on outward movement of the block 46, the toggle-links 44 are extended for gripping the jaws 33 on the heel G and, reversely, on inward movement of the block 46, the jaws 33 are released from the heel.

At its inner end, the block 46 is suitably chambered for slidably receiving a cam-follower or plunger 48 resiliently supported in the block 46 by means of a suitable spring or compression member 49 for endwise yielding sliding engagement with a fixed edge cam 50 mounted on the stud 5, the cam 50 including a rising or jaw-closing portion a, a heel-gripping or holding dwell b, a falling or jaw-opening portion c, and a rest or jaw-released portion d merging into the rise a, each preferably approximately encompassing 90 degrees of the periphery of the cam 50, as best seen in Figures 3 and 5.

The plungers 48 are normally biased on the cam 50 in jaw-opening direction by means of a spring 51 engaged between the lever studs 43, which, for such purpose, project above the plane of the levers 30, as best seen in Figure 8, whereby, on step-by-step rotation of the table C, the plungers 48 of the respective chucks E are yieldingly in cam-circumferential movement engaged with the successive cam-portions a, b, c, d, for reciprocation of the respective blocks 46 for, in turn, actuating the toggle-links 44 for correspondingly swinging the chuck-levers 30 for, likewise in turn, opening and closing the jaws 33, as best seen in Figure 3, the levers 30, in their described movement, also disposing the respective chuck-gripped heels centrally on the corresponding diametrical axes of the table C.

Thus, in sequence, each particular plunger 48 is actuated by the cam 50 for, firstly, through 70 and by yielding co-operation of the spring 49, shifting the block 46 outwardly for closing the chuck E on the heel G, when the plunger 48 engages the rising cam-portion a, then, secondly, for maintaining the chuck E in heel-gripping po- 75

sition, when the plunger 48 is on the cam-portion *b*, then, thirdly, for releasing the chuck *E* from the heel *G*, when the plunger 48 is on the cam-portion *c*, and, finally, for maintaining the chuck 5 *E* in open-heel-receptive position, while the plunger 48 is on the cam-portion *d*.

During a complete revolution of the table *C*, each chuck *E* thereof occupies successively, during the rest-periods intervening between the step-by-step rotatory actuation of the table *C*, certain positions indexed with relation to the carriage *B* and hereinafter designated as the heel-loading station *I* towards the front of the machine, the heel-chucking station *II* towards one side of the machine, the heel-grooving station *III* towards the rear of the machine, and the heel-unloading station *IV* towards the other side of the machine, as best seen in Figure 3.

The table *C* is indexed for disposing the chucks 20 *E* at such successive stations *I*, *II*, *III*, and *IV*, by means of a series of four notches 52 equally spaced around the periphery of the table *C* and engaged successively by a detent-pawl or latch-lever 53 mounted, as at 54, for oscillation on the 25 carriage *B* and having link-connection, as at 55, with the free end of a dog 56 mounted, as at 56', for oscillation also on the carriage *B* adjacent a side thereof.

The dog 56 carries a roller 57 laterally projecting from the carriage *B* for, at certain presently appearing movements of the carriage *B*, engaging a trip or catch 58 pivoted, as at 59, on a bracket 60 supported suitably from the bed *A*. The trip 58 is biased by a spring 61 against a 30 stop 62 for tripping the dog 56 for releasing the detent 53 from the notch 52 on forward movement of the dog 56 with the carriage *B* past the trip 58, and for yielding to the dog 56 on ensuing rearward movement of the carriage *B*, as will 35 presently appear. The dog 56 is engageable with a stop 63, and the detent 53 is biased for notch-engagement by a spring 64, as best seen in Figures 3 and 7.

Disposed at the grooving-station *III*, is a heel-cutting or concaving mechanism, which includes an axially vertical end-mill or cutter-head *H* endwise projecting upwardly through an aperture 65 in the bed *A* into an elongated slot 66 in the carriage *B* in the longitudinal center line thereof, as best seen in Figure 7, for effecting cutting operation in the attaching face of a heel *G* disposed in inverted or upside-down position at the station *III*, the cutter *H* being mounted on the upper end of, and rotatable by and with, a vertical shaft or spindle 67 journaled in suitable upper and lower bearings 68, 69, respectively, mounted suitably on the frame of the machine. The lower bearing 69, however, is of the closed-end or so-called step-bearing type and is mounted 50 for vertical adjustment in the machine, such adjustment being effected by means of a suitably provided take-up screw 70, as will be understood from Figure 2, for varying the position of the cutter *H* in the slot 66 above the horizontal plane 55 or level of the heel-gripping notches 34, as best seen in Figure 6, and the shaft 67 is equipped with a pulley 71 engaged by a belt 72 driven by a motor 73 for effecting cutting actuation of the cutter *H* on a gripped heel *G* fed to the cutter *H* on rearward movement of the carriage *B*, as 60 presently more particularly appears.

At the beginning of the heel-concaving operation, however, the carriage *B* and its supported table *C* are in forwardly shifted position on the 65 bed *A* for disposing the heel *G* at the station *III*

in forwardly spaced relation to the cutter *H*. For hence engaging the gripped heel *G* with the cutter *H*, the carriage *B* is shifted in what we may designate an approximately horse-shoe path, that is, in an oblique rearward and outward movement merging into an arcuate transverse or cross-movement, in turn, merging into an oblique forward and inward movement for return to the starting point, such travel of the carriage *B* occurring during each pause or indexed period of the table *C*, whereby the particular heel *G* disposed at the cutting station *III* is caused to traverse the cutter-head *H* for effecting concave-grooving co-operation thereof with the heel in a horse-shoe or loop-like path, as best 15 seen in Figure 9, for channelling or forming the concave 74 of the heel *G*, as will be understood from Figure 6.

For effecting such horse-shoe movement of the heel *G* on the cutter *H*, the carriage *B* is, in the 20 first instance, reciprocated longitudinally on the bed-plate *A* by means of a crank 76 having link-connection, as at 77, with the carriage *B*, the crank 76 being rotarily actuated by means of a vertical shaft 78 journaled suitably in the frame 25 of the machine and having driving connection, preferably by a chain-and-sprocket arrangement 79 with the shaft 23 for reciprocatory actuation of the carriage *B* in synchronism with the table-indexing mechanism *D*, as best seen 30 in Figure 7.

Concurrently with the reciprocatory movement of the carriage *B*, the same is laterally shifted first toward one or the right-hand side of the machine (having reference to Figure 3), and 35 then toward the other or left-hand side of the machine, by a mechanism which includes longitudinally aligned transversely spaced pairs of complementary edge or plate cams 80, 81, the pair of cams 80 being disposed on the right-hand 40 side of the machine and the pair of cams 81 being disposed on the left-hand side thereof.

The cams 80, 81, are mounted on respective shafts 82 upstanding for rotation in the bed-plate *A* of the machine, and the shafts 82 carry respective sprockets 83 engaged by an endless belt or chain 84, as shown, the belt or chain 84 being likewise trained over a driving-sprocket 85 mounted suitably on the crank-shaft 78, whereby the cams 80, 81, are driven in unison with the 50 shaft 78, as best seen in Figures 5 and 7.

Each of the cams 80, 81, includes a dwell-portion *e*, a lift-portion *f*, and a fall-portion *g* merging into the dwell *e*, the pair of cams 80 being opposite hand to the pair of cams 81, and the latter being in lag, operatively speaking, by 90 degrees or at right-angles to the cams 80. Depending from the carriage *B* adjacent to, and for co-operation with, the respective pairs of opposite cams 80, 81, are also respective pairs of transversely spaced cam-blocks 86, 87, having parallel cam-engaging faces 88. It will be understood that, when the blocks 86 at their respective faces 88 engage the fall *g* of the adjacent cams 80, the blocks 87 at their respective faces 88 engage the lift *f* of the opposite cams 81, and vice-versa, as will be readily understood from Figure 7; the pairs of opposing blocks 86, 87, having thus, as may be said, constant diametrical relationship with respect to the corresponding pairs of opposite cams 80, 81.

The blocks 86 and 87 on their respective outer sides are formed with irregularly shaped cam-faces 89, 90, respectively co-operable with also respective rollers 91, 92, journaled for such pur- 75

- pose on the carriage-supporting pins 2, the cams 80, 81, being preferably disposed opposite the respective rollers 91, 92 for engaging the blocks 86, 87, therebetween. The cam-faces 89 are opposite hand to the cam-faces 90, both cams 89, 90, being formed in suitably complementary shape to, and for roller-guided co-operation with, the cams 80, 81, respectively.
- Each of the cam-faces 89 includes a fall *h* for engaging a roller 91 when the lift *f* of a cam 80 is advancing on the block 86 and a lift or incline *k* for engaging a roller 91 as a cam 80 retracts its lift *f*, the lift *k* merging into a parallel or straight portion *m* for engaging the roller 91 as the cam 80 engages its dwell *e* with a block 86, as best seen in Figure 3, the block 86, however, being disengaged from its roller 91 when the cam 80 opposes its fall *g* to the block, as best seen in Figure 7.
- The blocks 87 co-operate with the cams 81 and rollers 92 in a similar, but reverse, manner, both pairs of blocks 86, 87, however, engaging their straight portions *m* with the respective rollers 91, 92, for centralizing the carriage B on the bed A when the carriage B is in its forward non-cutting position for ensuing indexing movement of the table C on the carriage B, as presently appearing.
- In use and operation, initially the plates 37 are set or adjusted suitably to the longitudinal dimensions of the particular heels, as described, and the cutter-head H is, by manipulation of the cutter-spindle lifting-screw 70, adjusted relatively to the concaving datum plane provided by the jaw-notches 34 to the depth of the concave to be made in the heels.
- In Figure 3 is illustrated the relative positions of the parts of the machine at the conclusion of the table-indexing movement thereof, the carriage B being then in partially rearwardly shifted position, at which time the chuck E at the station I is in opened heel-receptive position, the chuck E at the station II is in closed heel-gripping position, the chuck E at the station III is also in closed heel-gripping position, but disposed or retracted forwardly from the cutter H, and the chuck E at the station IV is in opened heel-releasing position.
- The detent 53 likewise is engaged with an indexing notch 52 and the dog 56 is disposed forwardly of, and released from, the catch 58 for indexing the table C on the carriage B, all as shown in Figure 3, and the pawl-and-ratchet mechanism D is at the terminus of its table-rotating stroke, as shown in Figure 4.
- The parts being in such described positions, the first particular heel G to be concaved is deposited or loaded in the particular chuck E then disposed at the loading station I, the operator grasping the top lift portion of the heel with the breast of the heel frontwise presented, and then, by forwardly inclining the heel, inserting the shank lip of the heel downwardly under the positioning plate 37 for resting the heel G on the heel-supporting plate 3, 4, in the pocket 36. As has been stated, an interval of time elapses between each indexing movement of the table, during which respective intervals the carriage B and table C are reciprocated on the bed A approximately in the diametrical plane of the cutter H for heel-concaving purposes, as will presently more fully appear. Thus ample time is permitted or allowed the operator for safely placing the particular heels in position for chuck engagement.
- At the next ensuing indexing movement of the

table C, the operator shifts the heel to bear at its breast on the plate 37 for radially positioning the heel in the particular chuck E and continues to so hold said heel G in said chuck during the indexing movement of the table, the jaws 33 then approaching or closing upon the so-positioned heel. As soon then, in the operation of the machine, as the heel is gripped between the jaws 33, the operator releases his hand from the heel, at about which time the heel has reached the heel-gripping position II of the machine.

Then on the next succeeding indexing movement of the table C, the so gripped heel G is shifted to the concaving station III, and the machine now automatically manipulates said heel for feeding the same radially, as it may be said, to and from the cutter H. It will thus be seen that at all times during heel concaving operations, the hand of the operator is remote, and in fact on the opposite side of the machine, from the cutter H, as will be clearly understood from Figure 3, thus wholly obviating the possibility of dangerous proximity of the operator's hand to the cutter.

During each heel-concaving operation of the machine, the carriage B is shifted rearwardly on the bed A by means of the crank 76 and link 77. Concurrently with such carriage movement, the cams 80 advance their lifts *f* on the cam-blocks 86 for shifting the carriage B laterally to one or the right hand side of the machine, reference being had to Figure 3. At the same time, the opposite cam-blocks 87 are drawn upon the falls *g* of the cams 81 and depart, as has been described, from their rollers 92, the rearward movement of the carriage B meanwhile successively disposing the inclines *k* and falls *h* of the block faces 89 opposite to their rollers 91.

As the cams 80, during their carriage-shifting rotation, recede, however, from the blocks 86, the opposite pair of cams 81 advance their lifts *f* upon the blocks 87, and the falls *h* of the cam-faces 90 being now opposite their rollers 92, the carriage B is reversely laterally shifted toward the left-hand side of the machine, the blocks 86 departing from their rollers 91, as best seen in Figure 7.

Meanwhile the crank 76 moves past its rear dead center for returning the carriage B in forward direction, and, the cams 81 correspondingly rotarily receding from the blocks 87, the rollers 92 successively engage the inclines *k* and straight-portions *m* of the cam-faces 90 for centralizing the carriage B on the bed A, the opposite rollers 91 meanwhile engaging the portions *m* of the cam-faces 89, whereby the blocks 86, 87, are again engaged between the cams 80, 81, and rollers 91, 92, respectively.

Meanwhile, further, the cutter H, being rapidly rotated by its spindle 67, grooves a channel 60 or concave 74 in the heel G, as seen in Figure 6. Figure 9 illustrates diagrammatically the path of the cutter H with respect to the particular heel G, it being borne in mind that actually the axis of the cutter H is stationary and that the heel G 65 moves relatively thereto. In such diagram, *p* represents the position of the cutter H when the carriage B is in extreme forward central position, and *r* represents the position of the cutter H when the carriage B is in intermediately rearwardly shifted position preparatory to feeding the heel G to the cutter H. Similarly, the position of the cutter H is represented at *s* when the carriage B is in extreme right-hand shifted position, at *t* when the carriage B is in extreme rear central 75

position, and at *u* when the carriage B is in extreme left-hand shifted position, the approximate path of the axis of the cutter H for grooving the concave 74 in the heel G being indicated by the line *r*—*s*—*t*—*u*—*r*, which path, as will be seen, is substantially parallel with the rim of the heel.

As clearly shown in Figure 9, the direction of rotation of the end mill or cutter H is such that its respective cutting edges 93 advance toward the uncut portions of the heel-body for effecting inward cutting action from the heel-rim 35 approximately toward the middle of the concave 74, whereby the cutting-thrust is directed toward the solid uncut portions of the heel-body rather than toward the relatively thin and fragile heel-rim or edge 35 of the heel G, as has heretofore, so far as we are aware, been the practice. Thus our machine, in cutting the concave 74, substantially eliminates breakage and chipping of the heel-rim 35, with resulting improvement in the quality of the product of the machine.

In the meantime, in its rearward movement, the carriage B carries the dog 56 past the catch 58, the latter swinging on its pivot 59 under yielding tension of the spring 61, and the parts then appearing as shown in Figure 7. However, on now occurring forward movement of the carriage B, the dog 56 engages its roller 57 with the catch 58, which, impinging against the stop 62, actuates the dog 56 for, through the link 55, swinging the latch-detent 53 for disengaging the same from its engaged notch 52 in the table C.

The table C being thus unlatched, a concaving operation being completed, the now-concaved-heel G being, on the forward movement of the carriage B, forwardly shifted and cleared from the cutter H, as indicated at *r* in Figure 9, and the pawl-and-ratchet mechanism D having in the interim moved to the position shown by dot-dash lines in Figure 4, the table C is rotarily indexed a quarter-turn as the mechanism D moves from dot-dash position to full-line position, as shown in Figure 4, the carriage B meanwhile moving to extreme forward position and partially rearwardly therefrom approximately along the path *r*—*p*—*r* of Figure 9.

The forward movement of the carriage B carries the dog 56 past the catch 58, whereby the detent 53 is, by the spring 64, biased on the rim 50 of the table C for, on rotation thereof, entering the next successive notch 52 therein for, in turn, latching the table C in its newly indexed position, the concaved-heel G being shifted to the unloading station IV for removal from the machine, preferably after another heel has been deposited in the machine at the loading station I, as seen in Figure 3.

In practice, the contour of the concave 74 formed in the heel G may be varied, by changing the shape or form of the cutter H and the table actuating cams, from the type shown in Figures 6 and 7, wherein a slight ridge exists along the medial line of the concave, to a type of concave having a flat-bottom with more or less abruptly curved sides for most conveniently fitting the skived outsole of the shoe, as will be understood by those skilled in the art.

In an analogous manner, different sizes of heels may be run on the machine by simply changing the cutter H, a cutter of large-diameter being employed for a large heel, and a smaller diameter cutter for a smaller heel, advantage being taken of the fact that, in the heel-manufacture art as at present practiced, the plan-contours of heels of different sizes form an homologous series.

The depth of the concave 74 in the heel is regulated by elevating or lowering the cutter H relatively to the plane of the jaw-notches 34, in which latter the heel-rim 35 is gripped, and which, as may be said, thus establish the datum-plane for the work.

As best seen in Figures 3 and 6, a guard 94 embracing the cutter H depends in rearwardly disposed position from the carriage B for chute-wise delivering the shavings resulting from the 10 concaving operations.

As will be understood from Figure 3, the operation of the machine is of a continuous nature. After each indexing movement of the table C, for example, the concaved heel is removed from the 15 station IV and an uncut heel deposited in the machine at the station I, the successive step-by-step movement of the table C serving to bring the deposited heels one at a time to the concaving station III for operation of the cutter H on 20 the particular heel. And it will be seen that, inasmuch as the operator's hand is at all times wholly remote from the cutter H, as has been said, the speed of operation may with perfect efficiency and safety be at a highly productive and 25 economical rate.

It will be understood that changes and modifications in the form, construction, arrangement, and combination of the several parts of our heel-concaving machine may be made and substituted 30 for those herein shown and described without departing from the nature and principles of our invention.

Having thus described our invention what we claim and desire to secure by Letters Patent is— 35

1. A heel-concaving machine including a cutter, in combination with a chuck comprising opposingly swingable jaw-carrying levers, a toggle-linkage connecting the levers, a block having shiftable toggle-knuckling co-operation with the 40 linkage, and cam-means co-operable with the block for actuating the levers and their carried jaws for gripping a heel for holding the same during concaving operation of the machine.

2. A heel-concaving machine including a cutter, in combination with a chuck comprising opposingly swingable jaw-carrying levers, a toggle-linkage connecting the levers, a block having shiftable toggle-knuckling co-operation with the linkage, cam-means co-operable with the block 50 for actuating the levers and their carried jaws for gripping a heel for holding the same during concaving operation of the machine, and tensional means for biasing the block on the cam for reversely actuating the levers and their carried jaws 55 for releasing the heel.

3. A heel-concaving machine including a cutter, in combination with a chuck comprising opposingly swingable jaw-carrying levers, and means for actuating the levers and their carried 60 jaws for gripping a heel for holding the same during concaving operation of the machine, said means including a toggle-mechanism, a cam, and a yielding connection between the toggle-mechanism and the cam.

4. A heel-concaving machine comprising, in combination, a cutter, a shiftable carriage, a table mounted for rotation on the carriage, a series of circumferentially spaced heel-gripping chucks on the table, and means for effecting step- 70 by-step rotation of the table for disposing the respective chucks successively in position for, on shifting movement of the carriage, feeding a chuck-gripped heel to and from the cutter.

5. A heel-concaving machine comprising, in 75

- combination, a cutter, a carriage shiftable relatively to the cutter, a table, a series of circumferentially spaced heel-gripping chucks on the table, the table being mounted for step-by-step 5 rotation on the carriage for disposing the respective chucks successively in position for engagement of a gripped heel with the cutter, and mechanism for shifting the carriage for feeding a table-positioned heel to and from the cutter.
- 10 6. A heel-concaving machine comprising, in combination, a cutter, a reciprocal carriage, a rotary table mounted on the carriage, a series of circumferentially spaced heel-gripping chucks on the table, means for rotating the table for disposing the respective chucks successively in position for engagement of a chuck-carried heel with the cutter, and means for reciprocating the carriage for feeding the table-positioned heel to and from the cutter in synchronism with the table-rotating means.
- 15 7. A heel-concaving machine comprising, in combination, a cutter, a frame, a carriage reciprocal on the frame, a heel-carrying table rotatable on the carriage, detent means for latching the table to the carriage, and means including a dog for releasably actuating said detent and a catch on the frame for, on reciprocation of the carriage, actuating the dog for releasing the table for rotation thereof on the carriage.
- 20 8. A heel-concaving machine including, in combination, an axially vertically disposed end-mill, and a chuck comprising opposingly shiftable jaws engageable with the upper rim of a heel for holding the heel in inverted position over and with its attaching face presented to the mill during a concaving operation of the machine.
- 25 9. A heel-concaving machine including, in combination, an axially vertically disposed end-mill, and a chuck comprising opposingly shiftable jaws having longitudinal grooves adjacent their lower margin engageable with the upper rim of a heel for holding the heel in inverted position over and with its attaching face presented to the mill during a concaving operation of the machine.
- 30 40 10. A heel-concaving machine including, in combination, an axially vertically disposed end-mill, a chuck comprising co-operable shiftable jaws for gripping a heel at its upper rim, and means for actuating the jaws for gripping the heel rimwise for holding the same in inverted position over, and with its attaching face presented to, the mill during a concaving operation of the machine.
- 45 55 11. A heel-concaving machine including, in combination, an axially vertically disposed end-mill, a chuck comprising opposingly swingable levers, grooved jaws on the levers for gripping a heel rimwise, a spring having connection with the levers for normally biasing the jaws into open position, and means for actuating the levers for yieldingly closing the jaws for gripping the heel rimwise for holding the same in inverted position over, and with its attaching-face presented to, the mill during a concaving operation of the machine.
- 60 70 12. A heel-concaving machine including, in combination, an axially vertically disposed end-mill, a chuck comprising co-operable shiftable jaws for gripping a heel rimwise, means for normally biasing the jaws into open position, and means including a toggle-linkage and a cam co-operable therewith for actuating the jaws for yieldingly closing the jaws for gripping the heel rimwise for holding the same in inverted position
- over, and with its attaching face presented to, the mill during a concaving operation of the machine.
13. A heel-concaving machine comprising, in combination, an axially vertically disposed end-mill, and means including a table axially rotatable and bodily shiftable with respect to the mill for automatically feeding a series of heels respectively at successive intervals to, over, and from the mill. 5
14. A heel-concaving machine comprising, in combination, an axially vertically disposed end-mill, a table movable in a plane disposed at right angles to the vertical axis of the mill, an annular series of heel-gripping chucks on the table, and mechanism for axially rotating and bodily shifting the table with respect to the mill for successively disposing the gripped heels over the mill. 10
15. A heel-concaving machine comprising, in combination, an axially vertically disposed end-mill, a carriage shiftably movable in a plane disposed at right angles to the vertical axis of the mill, a table mounted for shiftable movement with, and being also axially rotatable relatively to, the carriage, an annular series of heel-gripping chucks on the table, and mechanism for bodily shifting the carriage and table and axially rotating the table with respect to the mill for successively disposing the gripped heels over the mill. 15
16. A heel-concaving machine comprising, in combination, a slotted shiftable carriage, an axially vertically disposed end-mill projecting upwardly in the slot of the carriage, a rotary table 35 on the carriage, an annular series of chucks on the table for engagement with the rim of respective inverted heels, and means for synchronously shifting the carriage and actuating the table for successively disposing the gripped heels 40 over, and with their respective attaching faces presented to, the mill.
17. A heel-concaving machine comprising, in combination, an axially vertically disposed end-mill, a table movable in a plane disposed at right angles to the vertical axis of the mill, a heel-gripping chuck on the table, and means for both automatically actuating the chuck for gripping a heel and moving the table with respect to the mill for disposing the gripped heel over the mill. 45
18. A heel-concaving machine comprising, in combination, an axially vertically disposed end-mill, a stationary edge-cam in spaced relation to the mill, a shiftable table revolvable about the cam, jaws on the table co-operable for gripping 55 a heel, means for rotarily actuating the table, means actuatable by the cam on revolution of the table for actuating the jaws for gripping a heel, and means for shifting the table for positioning the gripped heel over the mill. 50
19. A heel-concaving machine including, in combination, an axially vertically disposed end-mill, a peripherally apertured table, a chuck comprising a pair of pivoted arms for grippingly engaging the opposite side faces of a heel for 65 holding the same in the aperture of the table and over the mill, and means including a plate mounted on and co-operable with the table for engaging the breast of the heel at said aperture for gaugingly locating the heel in the chuck for engagement by the mill. 60
20. A heel-concaving machine including, in combination, an axially vertically disposed end-mill, a peripherally apertured table, a chuck comprising a pair of pivoted arms for grippingly en- 75

gaging the opposite side faces of a heel for holding the same in the aperture of the table and over the mill, and means including a plate mounted for slideable adjustment on and co-operable with the table for engaging the breast of the heel at said aperture for gaugingly locating the heel in the chuck for engagement by the cutter.

21. A heel-concaving machine comprising, in combination, an axially vertically disposed end-mill, a shiftable table having a heel-accommodating peripheral aperture, a chuck operatively mounted on the table for gripping a heel in said aperture, and mechanism for actuating the table for disposing the aperture about, and the gripped heel over, the mill.

22. A heel-concaving machine comprising, in combination, an axially vertically disposed end-mill, a shiftable rotary table having a series of spaced heel-accommodating peripheral apertures, a series of chucks operatively mounted on the table for gripping the heels in the respective apertures, and mechanism for intermittently actuating the table for disposing the respective apertures successively about, and the gripped heels respectively over, the mill.

23. A heel-concaving machine comprising, in combination, an axially vertically disposed end-mill, a table rotatably shiftable in a plane disposed at right angles to the vertical axis of the mill, the table having a series of spaced heel-accommodating peripheral apertures, a series of heel-gripping chucks operatively mounted on the table for gripping the heels in the respective apertures, means for effecting step-by-step rotation of the table for presenting the respective apertures successively toward the mill, and means for synchronously shifting the table for successively positioning the gripped heels over the mill.

24. A heel-concaving machine comprising, in combination, an axially vertically disposed end-mill, a table rotatably shiftable in a plane right angularly disposed to the vertical axis of the mill, the table having a series of spaced heel-accommodating peripheral apertures, a series of heel-gripping chucks operatively mounted on the table for gripping the heels in the respective apertures, means including a pawl-and-ratchet mechanism for effecting step-by-step rotation of the table for presenting the respective apertures successively toward the mill, and means for synchronously shifting the table for successively positioning the gripped heels over the mill.

25. A heel-concaving machine comprising, in combination, an axially vertically disposed end-mill, a carriage shiftable in a plane right angularly disposed to the vertical axis of the mill, a table mounted for rotary movement on, and also shiftable with, the carriage, the table having a series of spaced heel-accommodating peripheral apertures, a series of heel-gripping chucks operatively mounted on the table for gripping the heels in the respective apertures, means including a pawl-and-ratchet mechanism for effecting step-by-step rotation of the table on the carriage for presenting the respective apertures successively toward the mill, means normally biased for retaining the table against rotary movement on the carriage, means for releasably actuating said retaining-means for chuck-positioning rotation of the table on the carriage, and means for shifting the carriage and its supported table for successively positioning the gripped heels over the mill.

26. A heel-concaving machine comprising an axially vertically disposed end-mill, in combina-

tion, a frame, a shiftable peripherally-apertured table disposed horizontally on the frame, means shiftable with the table relatively to the frame for supporting a heel in the aperture of the table with its attaching face disposed for cutting engagement by the mill, and means for shifting the table relatively to, and in a plane disposed at right angles to the vertical axis of, the mill for feeding the supported heel to, traversingly over, and from the cutting-edge of the mill.

27. A heel-concaving machine comprising an axially vertically disposed end-mill, in combination, a frame, a shiftable peripherally-apertured table disposed horizontally on the frame, means shiftable with the table relatively to the frame for supporting a heel in the aperture of the table with its attaching face disposed for cutting engagement by the mill, and means for shifting the table relatively to the mill and in a path wholly disposed at right angles to the vertical axis of the mill and partially straight and partially of approximate horse-shoe shape for feeding the supported heel to, traversingly over, and from the cutting edge of the mill.

28. A heel-concaving machine comprising an axially vertically disposed end-mill, in combination, a frame, a shiftable peripherally-apertured table disposed horizontally on the frame, means shiftable with the table relatively to the frame for supporting a heel in the aperture of the table with its attaching face disposed for cutting engagement by the mill, and means for shifting the table in a plane right-angularly disposed to the vertical axis of the mill for feeding the supported heel to, traversingly over the cutting-edge of the mill in a curvilinear path approximately parallel with the rim of the heel, and then from the mill.

29. A heel-concaving machine comprising, in combination, a slotted shiftable heel-supporting carriage, an end-mill axially vertically disposed in the slot of the carriage, a heel-supporting table on the carriage, and mechanism for shifting the carriage and table with a reciprocatory curvilinear movement for correspondingly feeding a supported heel to, traversingly over, and from the cutting-edge of the mill.

30. A heel-concaving machine comprising, in combination, a bed-plate, a slotted carriage shiftable on the bed-plate, an end mill axially vertically disposed in the slot of the carriage, a table on the carriage, a heel-gripping chuck on the table, and mechanism for shifting the carriage and table with a reciprocatory curvilinear movement over the bed-plate for correspondingly feeding a gripped heel to, traversingly over, and from the cutting-edge of the cutter.

31. A heel-concaving machine comprising, in combination, a bed-plate, a slotted carriage shiftable on the bed-plate, an end-mill axially vertically disposed in the slot of the carriage, a table on the carriage, a heel-gripping chuck on the table, and mechanism including a plurality of co-operable cam-members for shifting the carriage and table with a reciprocatory curvilinear movement over the bed-plate for correspondingly feeding a gripped heel to, traversingly over, and from the cutting-edge of the cutter.

32. A heel-concaving machine comprising, in combination, a slotted shiftable heel-supporting carriage, an end mill axially vertically disposed in the slot of the carriage, and mechanism for shifting the carriage with a reciprocatory ovaloid movement for correspondingly feeding a supported heel to, traversingly over, and from the cutting-edge of the mill, said mechanism includ-

ing a pair of spaced complementary cams and opposing cam-blocks on the carriage having cam-following engagement with the cams and rollers on the bed-plate having co-operation with the 5 respective cam-blocks.

33. A heel-concaving machine comprising, in combination, a frame, a horizontal bed-plate on the frame, a bearing mounted for adjustment on the frame, an end-mill supported by and axially 10 vertically upstanding from the bearing, a carriage shifttable on the bed-plate in a plane right-angularly disposed to the vertical axis of the mill, a peripherally-apertured table mounted on and movable with the carriage, means on the table 15 for supporting a heel in the aperture thereof with its attaching face presented for cutting engagement by the mill, mechanism for shifting the carriage and table bodily for feeding the supported heel to, traversingly over, and from the cutting edge of the mill, and means for adjusting the bearing for shifting the mill relatively to the table for regulating the depth of the concave to be cut in the heel.
34. A heel-concaving machine comprising, in combination, a frame, a horizontal bed-plate on the frame, a bearing mounted for adjustment on the frame, an end-mill supported by and axially vertically upstanding from the bearing, 20

a carriage shiftable on the bed-plate in a plane right-angularly disposed to the vertical axis of the mill, a peripherally-apertured table mounted on and movable with the carriage, means on the table for supporting a heel in the aperture thereof and establishing a datum plane for concaving the attaching face of the heel, mechanism for shifting the carriage and table bodily for feeding the supported heel to, traversingly over, and from the cutting-edge of the mill, and means for adjusting the bearing for shifting the mill with respect to said plane for selectively varying the depth of the concave to be cut in the heel. 5

35. A heel-concaving machine comprising, in combination, an adjustable end-mill axially vertically disposed, a heel-supporting carriage shifttable for feeding a supported-heel to, traversingly over, and from the cutting-edge of the cutter, heel-gripping jaws on the carriage having notches for engaging the rim of a heel for establishing a 20 concaving datum plane, and means for adjusting the cutter with respect to said plane for selectively varying the depth of the concave to be cut in the heel. 10 15
